SAMUEL F. BOUTON AND NATHAN P. AMES, OF CHICAGO, ILLINOIS.

Letters Patent No. 74,747, dated February 25, 1868.

IMPROVED SPRING-BED BOTTOM.

The Schedule referred to in these Letters Patent and making part of the same.

TO ALL WHOM IT MAY CONCERN:

Be it known that we, SAMUEL F. BOUTON and NATHAN P. AMES, of Chicago, in the county of Cook, and State of Illinois, have invented a new and useful Improvement in Spring-Bed Bottoms; and we do hereby declare and make known that the following is a full, clear, and exact description of the same, reference being had to the accompanying drawings, and the letters and figures marked thereon, which form part of this specification.

Our said invention relates to that class of spring-bed bottoms in which spiral springs are employed to support slats upon which the mattress or bed rests; and it consists in a novel mode of securing the upper ends of the spiral springs to the aforesaid slats, so that the springs may be retained in the desired vertical position, while at the same time the springs may when desired, be readily detached from the slats and their lower supports, thus enabling the entire bed-bottom to be taken apart and put up again at pleasure.

To enable those skilled in the art to make and use our said invention, we will proceed to describe the same with particularity, making reference, in so doing, to the drawings aforesaid, in which—

Figure 1 represents a plan or top view of our invention,

Figure 2 a side view of the same, and

Figure 3 an enlarged view of one of the springs, as seen from beneath, showing the mode of attachment to the slats aforesaid.

Similar letters of reference, in the several figures, denote the same parts of our said invention.

A represents a bedstead, provided with two cross-slats or pieces, marked B, upon which one end of the spiral springs D rest, being secured in place by the entering of the ends of the wire of which said springs are formed, marked a, into suitable holes or sockets, b, in the supporting-slats B, as shown in the drawings. Upon the said springs, arranged as shown, are placed and secured, as hereinafter described, a series of longitudinal slats, C, upon which the mattress or bed is arranged or placed. The said springs are secured removably to the slats in the following manner: The wire forming the upper coil of the springs is bent out, as shown at d, in fig. 3; then, doubling back, is again bent, substantially in the direction of a tangent to the circumference coil, forming a straight arm of a suitable length from e. Upon the slat C is secured, by screws, nails, or their equivalent, a metallic strip, bent up as shown, so as to form a socket or semi-tube, e, into which the arm e, upon the spring, may enter, and from which it may be withdrawn.

From the above description it will be seen that by this arrangement and construction, the springs are kept in a vertical position, thus retaining the form in which they have the greatest elasticity, the socket e, acting upon the arm e, preventing any lateral displacement or tipping over sideways, while the projection d, or its equivalent, to prevent the rotation of the arm e in the socket e, prevents any tipping of the springs towards the head or foot of the bed. Thus the springs are securely kept in position, and the slats C secured from lateral displacement, making a very superior and durable bed, which can, however, be taken apart for convenience in transportation, or moving from one room to another, and set up for use again, as desired, which is a very important and desirable feature. In order to more securely attach the springs to the slats a pin with a hook upon the end may be inserted in the slat, so as to clasp and hold the wire of the spring upon the slat, and so that by turning said hook around, it will release the coil, and permit it to be detached, as desired.

We claim the combination of the arms d and e, formed upon the coil of the spring D, as shown, and a socket, e, applied or secured to the slat C, in the manner and for the purposes specified.

SAMUEL F. BOUTON,
NATHAN P. AMES.
